UNITED STATES PATENT OFFICE

LARKIN R. SHAFFER, OF GARLAND, UTAH

LEVER-LATCHING DEVICE

Application filed July 25, 1928. Serial No. 295,242.

This invention relates to improvements in locking or latching mechanisms for levers, and particularly to a latching mechanism for the operating levers of what are commonly known as ground throw switches or stands.

One of the objects of the present invention is to provide a novel form of lever latch or keeper, and particularly a latch for the operating lever of a railway switch, the preferred arrangement being such as to permit the switch operating mechanism, including the switch operating lever, to operate automatically under force created by flanges of car wheels running through the switch when the points of the latter are not properly aligned. This automatic release feature prevents damage to the operating mechanism under abnormal conditions, such as outlined.

With these and other objects in view, the invention consists in certain novel details of construction and combinations and arrangements of parts, all as will hereinafter be more fully described and the novel features thereof particularly pointed out in the appended claims.

In the accompanying drawings:

Figure 1 is an elevational view of a latch or keeper adapted for use with a ground throw switch stand, the lever latching arm for the operating lever being shown in fully released position;

Fig. 2 is a vertical sectional view of the structure shown in Figure 1, the parts being shown in full lines in their locked position, and in their partially released position in dotted lines;

Fig. 3 is a top plan view of the structure shown in Figs. 1 and 2.

In the preferred construction, there is a slot 10 for the reception of the switch operating lever 11, shown in cross section in Fig. 2. Slot 10 is formed between two upright extensions, these extensions, for convenience, being termed a standard 12 and a guide post 13.

When the switch operating lever 11 is to be locked in the slot 10, a latch arm 14 is adapted to span said slot at a point above lever 11, said lever lying on the bottom of the slot when in locked position. Preferably, latch arm 14 is pivoted on a pivot pin 21 in

one of said stand extensions, guide post 13, in the present instance, and its free end projects laterally beyond standard 12, as shown in Fig. 2, when the arm is in lever locking position. For holding latch arm 14 in locking position, and thereby holding the switch safe under ordinary traffic conditions, the free end of said arm has pivoted thereto, a weight 15 that is movable by gravity to assume a position beneath a projection 16 on standard 12 when the arm is in locking position. Weight 15 is pivoted eccentrically on arm 14 and upon excessive strains on lever 11, as when the flanges of car wheels run through a switch that is not properly lined up, arm 14 is slightly raised and weight 15 brought into engagement with projection 16, with the result that said weight is partially rotated on its pivot until it assumes a position where it is free to ride from said projection. In this way, the operating lever 11 is releasably or yieldingly held in its locked position, and when abnormal conditions exist, as just outlined, arm 14 is free to raise, so that breakage or bending or other resulting damage of the stand and switch operating connections is prevented.

In order that the latch arm 14 will assume its locking position whenever operating lever 11 is moved down into slot 10, said arm has an extension or nose portion 17 formed thereon, which is movable into slot 10 when arm 14 is caused to assume its fully unlocked position, as shown in Figure 1. With nose 17 thus locked in slot 10, as lever 11 is lowered into slot 10, arm 14 will be turned on its pivot and after it has passed its pivotal center, weight 15 will cause it to flop over, so to speak, and assume its locked position.

In normal operation, latch arm 14 may be moved from locked to unlocked position by means of a foot pedal 18 carried on a second extension 19 of said latch arm. Nose 17 of the latch arm may also be provided with an aperture or eye 20, for the usual switch lock.

I claim:

1. In a lever latching device, the combination of a standard, a guide post spaced from said standard forming a lever receiving slot, a latch arm pivoted on said post and

movable to lever locking position across said slot, and cooperating elements on said standard and arm for yieldingly locking said arm in said slot.

5. 2. In a lever latching device, the combination of two upright extensions having a lever receiving slot between them, a latch arm pivoted on one of said extensions and having a free end adapted to project laterally beyond 10 the other extension when in lever locking position, and means carried by said arm and engageable with said other extension for holding said arm in lever locking position.

3. In a lever latching device, the combination of two upright extensions having a lever receiving slot between them, a latch arm pivoted on one of said extensions and having a free end adapted to project laterally beyond the other extension when in lever locking position, and means carried by said arm and engageable with said other extension for holding said arm in lever locking position, said holding means yieldingly engaging said other extension.

25. 4. In a lever latching device, the combination of two upright extensions having a lever receiving slot between them, a latch arm pivoted on one of said extensions and having a free end adapted to project laterally beyond 30 the other extension when in lever locking position, and means carried by said arm and engageable with said other extension for holding said arm in lever locking position, said holding means comprising a projection 35 on said other extension and a swingable weight carried by said arm movable by gravity to a position beneath said projection when the arm assumes its lever locking position.

5. In a lever latching device, the combination of two upright extensions having a lever receiving slot between them, a latch arm pivoted on one of said extensions and having a free end adapted to project laterally beyond the other extension when in lever 40 locking position, and means carried by said arm and engageable with said other extension for holding said arm in lever locking position, said holding means comprising a projection on said other extension and a 45 weight eccentrically pivoted on the latch arm and movable by gravity to a position beneath said projection when said arm assumes its locking position.

6. In a lever latching device, the combination of two upright extensions having a lever receiving slot between them, a latch arm pivoted on one of said extensions and having a free end adapted to project laterally beyond the other extension when in 50 lever locking position, and means carried by said arm and engageable with said other extension for holding said arm in lever locking position, said holding means comprising a projection on said other extension and a 55 swingable weight carried by said arm mov-

able by gravity to a position beneath said projection when the arm assumes its lever locking position, said weight being movable by said projection to release said arm and lever.

7. In a lever latching device, the combination of two upright extensions having a lever receiving slot between them, a latch arm pivoted on one of said extensions and having a free end adapted to project laterally beyond the other extension when in lever locking position, and means carried by said arm and engageable with said other extension for holding said arm in lever locking position, said holding means comprising a 70 projection on said other extension and a weight eccentrically pivoted on the latch arm and movable by gravity to a position beneath said projection when said arm assumes its locking position, said weight being movable on its pivot by said projection to release said arm and lever.

8. In a lever latching device, the combination of two upright extensions, there being a lever receiving slot between said extensions, a latch arm pivoted on one extension adapted to bridge said slot when in locked position, a projection formed integrally with said arm movable into said slot when the arm is in unlocked position, and a foot pedal formed integrally with said arm and its extension.

9. In a lever latching device having a lever receiving slot with upright extensions at opposite sides thereof, a latch arm pivoted on one extension adapted to bridge said slot and project laterally beyond the other extension when the arm is in locking position, and means for yieldingly holding said arm in locking position, said means comprising a weight movable to one side of the pivotal center of said arm when the latter is in unlocked position and movable to the opposite side of said center when the arm is in locked position.
